Inventor
Joseph S. Naylor
by Ormeig A. Hagel At'tys:

UNITED STATES PATENT OFFICE.

JOSEPH S. NAYLOR, OF CLEAR LAKE, IOWA.

CATTLE-LEADING RING.

Application filed January 30, 1923. Serial No. 615,821.

To all whom it may concern:

Be it known that I, JOSEPH S. NAYLOR, a citizen of the United States, and a resident of Clear Lake, in the county of Cerro Gordo 5 and State of Iowa, have invented a certain new and useful Cattle-Leading Ring, of which the following is a specification.

The object of my invention is to provide a ring of simple, durable and inexpensive 10 construction, especially designed for use on domestic animals such as cattle, as a means for the attachment of leading chains.

More specifically it is my object to provide a ring of this class which may be applied to the animal's nose and there firmly held without penetrating the wall between the animal's nostril; and

Further to provide a ring of this class in which the parts may be readily and quickly 20 separated as required in applying to or removing from the animal's nose, and then when it is inserted in position for use, the parts may all be readily and quickly connected with each other and firmly braced 25 against all movement, to thereby provide a permanent connection without danger of having the ring released.

My invention consists in the construction, arrangement and combination of the various 30 parts of the device, whereby the objects contemplated are attained, as hereinafter more fully set forth, pointed out in my claims, and illustrated in the accompanying drawings, in which:

Figure 1 shows a side elevation of a complete ring embodying my invention in a closed position.

Figure 2 shows a vertical, central, sectional view of the same.

Figure 3 shows an edge view of one of the double sections of which the ring is formed.

Figure 4 shows an enlarged, detail, sectional view on the line 4-4 of Figure 1; and

Figure 5 shows a side elevation of a modified form of my invention, the dotted lines show one of the sections moved to open position.

Referring to the accompanying drawings, it will be noted that each section of the ring is a duplicate of the other in many respects, and I will, therefore, first describe the parts or members of one of these sections, which 55 comprises a substantially semi-circular body

portion 10 preferably round in cross section and having at one end an oval knob 11 and at the other end a lug 12 of half the thickness of the body of the ring, and all arranged on one side of the longitudinal center of the ring, as shown in Figure 3. This lug 12 has an opening through it designed to receive a pivot pin 13.

At a point between the oval knob 11 and the lug 12 is a brace arm 14 formed integral 65 with the body 10 and projected inwardly to a point substantially in line with a line between the knob 11 and the pivot pin 13. This arm is substantially half the thickness of the body portion 10 and it is located on the side of the body portion opposite to the side at which the lug 12 is located, this arrangement being clearly illustrated in Figure 3. The arm 14 is formed with a screw threaded opening designed to receive a 75 screw 15.

In assembling the parts, I first place the two ring sections in position as shown in Figure 1, and then secure the pivot pin 13 in position so that the two parts are hinged 80 together. When this arrangement has been made attention is called to the fact that the lug 12 and the arm 14 of one of the members is arranged on the opposite side of the corresponding lug and arm of the other member, and when the screw 15 is put into position, then this arrangement of the arms and the lugs will strengthen and reinforce the device so that twisting strains applied to one of the knobs 11 and not to the other will not 85 be so likely to injure or break the pivot pin or the screw as would be the case if both the arm 14 and the lug 12 were on the same side of each section of the ring.

In Figure 4 I have illustrated the details 95 of the screw 15 and the arms 14. The arm 14 into which the screw is first inserted has its threads cut of slightly larger diameter than the threads of the screw. That is to say, the screw fits loosely, whereas the 100 threads in the other arm 14 into which the end of the screw is seated are made to fit more closely to the screw. Hence, when the screw is inserted and tightened the two arm members will be firmly secured together, and yet when it is desired to detach the device, the screw may be withdrawn until its end 105 remains seated only in the arm member having the large screw, which will hold the screw from becoming detached from the 110

2
arm, and thus prevented from being lost or misplaced as would be the case if only one of the arm members were screw threaded.

In the modified form shown in Figure 5, 5 each section of the ring is formed with a knob at one end and at the other end there is formed a complete ring 16 with an extension arm 17 beyond the ring 16 and the said ring and said arm are made of half the 10 thickness of the body of the ring proper, so that when the two ring members are assembled in the position shown in Figure 5, the thickness of the body of the ring will be substantially uniform throughout. Each 15 ring member is formed with a shoulder 18 designed to be engaged by the arm 17 to limit the inwardly swinging movement of the ring members. A pivot pin 19 is passed through the members adjacent to one side 20 of the ring 16 and a screw 20 is provided for connecting the parts on the side of the ring 16 opposite from the pivot pin.

In practical use, and assuming that the screw is seated only in one of the arms 14, 25 then the knobs 11 are placed in the animal's nose and the parts brought together and the screw 15 screwed into the other one of the arms 14, and when this is done, the device is ready for use as a leading ring. The space 30 between the arms 14 and the parts of the ring on which the lugs 12 are formed is designed to receive a snap hook for leading chains or rope, and when this is done then the arms 14 prevent the snap hoop or the 35 rope from sliding around the ring to a point where they might engage or injure the animal's nose. Hence these arms serve the double function of limiting the movement of the snap hook and at the same time firmly 40 brace and rigidly secure the ring members in their relative positions against movement in any direction.

Furthermore, by having the snap hook always held at the bottom of the ring and applying power to the snap hook to hold an animal, then one of the inner sides of the ring members will engage the enlarged base portion at the exterior of the nostril wall,

which will serve as a fulcrum, and the knob on the opposite member will press the wall 50 of the nostril laterally, thus applying a leverage or twisting movement instead of a straight pull as with the ordinary rings.

I claim as my invention:

1. An improved bull ring formed of two parts, each substantially semi-circular in outline and each having at one end a knob and at the other end a lug, a pivot pin connecting the two lugs together, and an arm formed on each member between the knob and the pivot pin extended across the ring and being provided with openings designed to receive a screw for holding the parts rigidly together, for the purposes stated. 55

2. An improved bull ring comprising two like members, each member being substantially semi-circular in outline and round in cross section, and being provided at one end with an oval knob and at the other end with a flattened lug, and each also being provided with an arm extended inwardly from the member, said arm and said lug each being of substantially half the thickness of the ring proper and being arranged on opposite sides of the longitudinal center of the ring, 75 a pivot pin connecting the said lugs, and a screw for connecting the said arms, one of said arms being formed with a screw thread to substantially fit the screw, and the other being formed with a screw thread to loosely 80 fit the screw, for the purposes stated. 70

3. An improved cattle leading ring comprising two substantially semi-circular members pivoted together at one end portion and each formed with a knob at the 85 other end, each member being formed with an integral arm between the pivotal point and the knob and said arms being shaped to lie in overlapping position when the members are in position for use and both arms 90 being formed with openings, and a screw secured in said openings for rigidly securing the members in position relative to each other.

Des Moines, Iowa, December 22, 1922.
JOSEPH S. NAYLOR.
